UNITED STATES PATENT OFFICE

2,608,154

MOISTENING MEANS FOR DUPLICATORS

Louis A. Smitzer and Henry D. Thompson, Chicago, Ill., assignors to Ditto, Incorporated, Chicago, Ill., a corporation of West Virginia

Application May 28, 1948, Serial No. 29,706

3 Claims. (Cl. 101—132.5)

1

The present invention relates to a duplicating machine of the spirit or wet process type that employs a moistening roller for applying a fluid, such as ethyl alcohol, on the face of each copy sheet as it is fed to the duplicating drum. Mounted on the drum is a master sheet that bears the written or typed material that is to be transferred onto the moistened face of the copy sheet. The ethyl alcohol serves as a solvent to aid in the transfer of the ink on the master sheet onto the copy sheet.

In a machine of this character the moistening fluid is fed onto the roller by a wick of felt or like material that engages the peripheral face of the material. In the present instance this wick receives its supply of fluid from a fountain that is disposed above the wick. A reservoir containing a supply of the fluid is located on the machine at a position below the fountain and a pump serves to pump the fluid to the fountain.

The present invention is primarily concerned with the pump means for feeding the liquid from the reservoir to the wick. This feeding may be accomplished both when the machine is not being operated and also at all times when the machine is in operation. In order to insure that the first copy sheet fed through the machine receives its impression from the master sheet, the fluid feed must be primed so that the moistening roller will have its peripheral face coated with the moistening fluid at the very outset. After the machine commences operating the fluid from the reservoir is fed to the moistening roller on a continuous basis to insure at all times a constantly moistened roller. The present invention provides a device that will accomplish both of these objectives, resulting in the production of uniformly clear reproductions on a large number of copy sheets including the very first sheet. A machine embodying this invention is simple and yet efficient.

The foregoing constitute some of the principal objects and advantages of the present invention, others of which will become apparent from the following description and the drawings, in which

Fig. 1 is a fragmentary, vertical, sectional view through a duplicating machine embodying the present invention;

Fig. 2 is a vertical sectional view through the machine shown in Fig. 1, the view being taken in the opposite direction;

Fig. 3 is an enlarged, vertical sectional view through a portion of the machine, the view being taken on the line 3—3 of Fig. 1;

Fig. 4 is a fragmentary, vertical sectional view taken on the line 4—4 of Fig. 2;

2

Fig. 5 is an enlarged, vertical, sectional view through the machine, the view being taken on the line 5—5 of Fig. 1;

Fig. 6 is an enlarged, vertical sectional view through a portion of the machine, the view being taken along the line 6—6 of Fig. 1;

Fig. 7 is an enlarged, horizontal sectional view through the primer button assembly, the view being taken on the line 7—7 of Fig. 5; and

Fig. 8 is likewise a horizontal sectional view taken through the primer button assembly, the view being taken along the line 8—8 of Fig. 5.

For purposes of illustration a single embodiment of the invention has been selected, though it is recognized that many changes may be made in this embodiment without departing from the intended scope and spirit of the invention.

Referring now to Fig. 1 of the drawings the invention is applicable to a standard duplicating

machine that includes a drum 10 that is mounted to rotate on a shaft 11. This shaft 11 as is customary is journaled in a pair of spaced side walls 12 (Figs. 1 and 2) of the machine and is adapted to receive on its peripheral face a master sheet 13 that is locked in place by means of a master sheet clamp indicated at 14. Mounted beneath the drum 10 is a pressure roller 15 that is adapted to rotate about a shaft 16 that is journaled in spaced pressure arms 16a. This pressure roller 15 engages the peripheral face of the drum 10 and serves to provide pressure contact against the master sheet 13 that is carried by the drum 10.

Mounted in front of the pressure roller 15 is a pair of cooperating feed rollers 17 and 18 mounted respectively on shafts 19 and 20. Shaft 20 is journaled in the spaced walls 12 of the machine, while shaft 19 is journaled in spaced pressure arms 19a.

Mounted at the forward end of the machine is a paper tray partially shown at 21 upon which copy sheets are initially placed for feeding between the feed rollers 17 and 18. The copy sheets are fed one at a time between these feed rollers by means of a paper feed mechanism generally indicated at 22 and are in turn fed between the pressure roller 15 and drum 10 by means of feed rollers 17 and 18, the drum 10 being rotated in the direction of the arrow A during this operation. The copy sheets leaving the drum 10 are deposited in a discharge paper tray 23.

Roller 18 in addition to serving as a feed roller in cooperation with roller 17 also serves as a moistening roller to initially moisten the upper surface of each copy sheet as it passes between the rollers. This roller 18 will therefore hereinafter

be referred to as a moistening roller. Mounted above the roller 18 is a fountain generally indicated at 24 that is secured to the machine by means of spaced brackets 25 (Fig. 3), each of which is supported on an attaching bracket 26 that includes a wall 27 that extends across the machine between spaced walls 12. This wall 27 is provided with a downwardly extending flange 28, to which each angle bracket 25 is riveted or otherwise secured. The attaching bracket 26 is further provided with flanges 29, each of which is bolted as at 30 onto one of the walls 12 of the machine. A guard plate 31 is likewise secured to the lower flange 28 of the attaching bracket 26 and extends downwardly to a position between the moistening roller 18 and the drum 10.

Adjacent to the moistening roller 18 is a wick assembly generally indicated at 32 that is suspended from the upper end of the attaching bracket 26 on an arcuate flange 33. Disposed above the arcuate flange 33 on each wall 12 of the machine is a limiting or stop pin 34 that serves to limit the movement of the wick assembly 32 during the time it is being removed from the machine or applied thereto. The actual structure of the wick assembly 32 and the manipulation thereof during its withdrawal from the machine form no part of the present invention. For purposes of the present description it will be sufficient merely to state that the assembly 32 includes a wick 35 that during normal operation of the machine is held firmly against the peripheral face of the moistening roller 18 as is best shown in Fig. 1. A more detailed description of the structure and operation of the wick assembly 32 may be found in the copending application of Herman A. Genz, Serial No. 25,341, filed May 6, 1948.

The fountain 24 comprises an inner pipe 36 (see Figs. 1 and 3) and an outer pipe 37 that is mounted concentrically about the inner pipe so as to provide an annular space or well 38 therebetween. The inner pipe 36 has a plurality of apertures 39 spaced lengthwise along the pipe providing communication between the interior of the inner pipe and the well 38. The outer pipe 37 has a plurality of apertures 40 spaced lengthwise thereof that serve as nozzles for directing a spray of fluid as shown in Fig. 1 in a downwardly direction toward the roller 18.

As shown in Figs. 1 and 6 a reservoir generally indicated at 41 is mounted in the lower region of the duplicating machine and comprises a cup-like container 42 that holds a quantity of fluid 43 that is adapted to be supplied to the fountain 24. This cup-like container 42 is supported on a pan or base plate 44 that is secured by means of bolts 45 to the spaced walls 12 of the machine. The container 42 is provided with a filling aperture formed by an internally threaded bushing 46 and a removable cap 47 is threaded into the bushing 46 to close the opening.

A pump assembly generally indicated at 48 is mounted on the container 42 and includes a pump body portion 49 that provides a pump cylinder 50 in which is mounted a piston 51. Extending downwardly from the body portion 49 is a shaft 52 that terminates adjacent to the bottom of the container 42 and is threaded at its lower end as at 53 to receive a cup-shaped bottom cap 54. The shaft 52 is provided with a longitudinal passage 55 extending therethrough that opens out through the lower end of the shaft and extends upwardly into the cylinder 50. The bottom cap 54 is apertured as at 56 to provide a

valve opening over which is mounted a movable ball valve 57 that is normally seated over the aperture or valve opening 56. A compression spring 58 is held against the ball valve 57 and normally holds the valve in its seated position. The lower end of the cup-shaped cap 54 is provided with passages 59 communicating with the interior of the container 42 and a screen 60 is secured to the cap 54 and encases the openings of passages 59.

The body portion 49 is further provided with an upwardly extending passage 61 that extends from the inside of cylinder 50 to an enlarged passage 62 that continues to the upper face of the body portion 49. A threaded cap 63 closes the upper end of the enlarged passage 62. A ball valve 64 is seated over passage 61 and is normally held in this seated passage by a compression spring 65.

Referring now to Fig. 6 a discharge passage 66 extends outwardly from passage 62 and communicates with a pipe 67 that extends from the pump assembly 48 horizontally through one of the walls 12 of the machine and then upwardly to a position opposite the fountain 24 (see Fig. 3) and then inwardly again through the machine wall 12 where it is attached to the end of the inner pipe 36 forming part of the fountain 24.

As best shown in Fig. 6 the bottom wall of the cup-shaped container 42 is apertured as at 68 and a removable cap 69 normally closes this aperture but can be removed for emptying the container 42.

Again referring to Fig. 1 the piston 51 is mounted on a shaft or plunger 70 that projects beyond the cylinder 50 and is threaded on its free end as at 71 to receive an adjustable collar 72. A fixed collar 73 is mounted on the shaft 70 intermediate its ends. A tension spring 74 is secured at one end as at 75 to the free end of the shaft 70 and at the other end as at 76 to a bracket 77 that is fixed as at 78 to the machine frame. Thus the piston shaft 70 is normally held by spring 74 in a retracted position shown in Fig. 1 but is adapted to be moved back and forth so as to cause the piston 51 to reciprocate in the cylinder 50 from a position shown in dotted lines at 51a (in Fig. 1) at the extreme inner end of the cylinder 50 to the solid line position indicated at 51. While the piston 51 is moving from the broken line position 51a to the solid line position 51 suction is created in the passage 55 of shaft 52 so as to raise the ball valve 57 off its seat and allow fluid from the reservoir 41 to be drawn up into the cylinder 50. During this movement of the piston 51 the ball valve 64 is retained on its seat. During the return stroke of the piston 51 from its solid line position to the broken line position 51a the lower ball valve 57 is again seated to close the passage 56 while the upper ball valve 64 is raised off its seat and the charge of liquid in the cylinder 50 is forced through pipe 67 (see Figs. 3 and 6) into the inner pipe 36 of fountain 24. The fluid thus fed into the inner pipe 36 of the fountain passes through apertures 39 into the annular space or well 38 and then through apertures 40 in the outer pipe 37 and finally down onto the wick 35 (see Fig. 1) and the surface of moistening roller 18.

In order to initially prime the fountain 24 so as to furnish fluid on the periphery of moistening roller 18 at the time the machine is first placed into operation a primer generally indicated at 80 (Fig. 2) is provided. This primer 80 includes a priming button 81 (Figs. 2 and 5)

that is slidably mounted in a supporting frame 82 that is bolted as at 83 onto one of the walls 12 of the machine. This priming button 81 is slidably up and down in the frame 82 and at its lower end rests on an arm 84 that is fixed to a shaft 85. This shaft 85 is journaled in the spaced walls 12 of the machine and intermediate the ends thereof carries an arm 86 (see Fig. 1) that projects upwardly and is bifurcated at its upper end to engage the adjustable collar 72 on piston shaft 70. Thus as the priming button 81 is pushed downwardly it engages arm 84 so as to cause shaft 85 to rotate in a direction such as to move the arm 86 (Fig. 1) in a clockwise direction to force the piston shaft 70 and hence the piston 51 to move toward the dotted line position 51a for the piston. Upon releasing the pressure from the priming button 81, the tension spring 74 (Fig. 1) returns the entire assembly to the solid line position shown in Fig. 1, thereby urging the priming button 81 to its initial position shown in Fig. 2. Thus by a repeated number of strokes of the priming button 81 the pump 48 is caused to operate to pump fluid into the fountain 24 and finally onto the wick 35 and moistening roller 18. After the fountain has thus been primed the machine is placed into operation and as the moistening roller 18 is caused to rotate the moistening fluid is spread over the peripheral surface of the roller by the wick 35. Thus by the time the first copy sheet is fed from the tray 21 by means of paper feed mechanism 22 between the feed rollers 17 and 18, the latter roller serving as the moistening roller has received its charge of moistening fluid so that it can effectively moisten the face of the first copy sheet.

Again referring to Fig. 2 a cam 87 is mounted on the shaft 11 that carries the drum 10. Thus as the drum is caused to rotate the cam 87 likewise is rotated. A bell crank 88 is pivotally mounted as at 89 on one side wall 12 of the machine and adjacent to one free arm of the bell crank 88 is provided a follower roller 90 that rides on the surface of cam 87. To the free end of the bell crank 88 is pivotally mounted as at 91 a link 92, the other end of which is pivotally secured as at 93 onto the free end of an arm 94. This arm 94 in turn is fixed with respect to a shaft 95 that is journaled as indicated in Fig. 5 in the spaced walls 12 of the machine. Mounted on the shaft 95 between its ends is an arm 96 (see Figs. 1 and 5) that is bifurcated at its upper end as indicated at 97 in Fig. 5 to straddle the piston shaft 70 and engage the fixed collar 73 on this shaft.

During normal operation of the machine as the cam 87 is caused to rotate along with the machine drum 10 the bell crank 88 is rocked back and forth on its pivot mount 89 through co-operation between the cam 87 and its follower 90 riding on the surface of the cam. This rocking movement of the bell crank 88 causes the link 92 to reciprocate back and forth so as to rock the arm 94 and the shaft 95. This rocking movement of shaft 95 conveys a similar rocking movement to the arm 96 (Fig. 1) and this in turn reciprocates the piston shaft 70 back and forth in exactly the same manner as previously described with respect to the movement of arm 86. Thus the pumping of the fluid from the reservoir 41 to the fountain 24 is effected during normal operation of the machine by virtue of the action of this arm 96 shown in Fig. 1.

A tension spring 97 secured at one end as at 75

98 to the arm 86 and at the other end as at 99 to the brackets 77 normally holds the arm 86 in the position shown in Fig. 1. A similar spring (not shown) is secured at 100 to the arm 96.

Thus there is provided a primer and moistening fluid operating device that is simple and yet effective in insuring at all times a supply of fluid on the moistening roller for all copy sheets that are fed into the machine commencing with the very first copy sheet at the time when the machine is first placed into operation. The moistening fluid used on the surface of roller 18 evaporates very rapidly so that after the machine has stood at rest for even a short period of time, the face of the moistening roller becomes dry. Following such period of rest the first copy sheet introduced into the machine would be apt to have a large margin left at the top if it were not for the primer forming the subject matter of the present invention.

Again referring to Figs. 2 and 5 a primer button 81 is provided at the lower end thereof with a stop pin 101 that engages the bottom edge of a cam plate 102 which limits the upward movement of the primer button.

Referring to Figs. 7 and 8 the primer button 81 is further provided with a vertically extending groove 103 that extends substantially throughout the length of the button member. A guide strip 104 is secured by means of bolts 105 to the wall 12 of the machine and is provided with a vertically extending corrugation or bead 106 that is adapted to fit in the groove 103 of the primer button 81. This bead 106 normally holds the primer button 81 and prevents rotation thereof. Thus the position of the stop pin 101 on the cam plate 102 is normally fixed by the cooperation between the bead 106 and cooperating groove 103, and in this condition for purposes of illustration may effect medium intensity lines that are reproduced on the copy sheets. In other words, with the primer button 81 disposed in the manner shown in the drawings the piston 51 is operated with a medium length stroke. If it is desired to increase the amount of moistening fluid initially deposited upon the moistening roller 18, the stroke of the piston 51 is increased in length by rotating the primer button 81 in a clockwise direction (as viewed in Figs. 7 and 8) so as to move the pin 101 further upon the plate 102, in which case the intensity of the inked impressions on the first copy sheets is increased. Conversely to decrease the intensity below the medium intensity condition, the primer button 81 is rotating in a counterclockwise direction as viewed in Figs. 7 and 8 from the medium position illustrated. An indicator plate 107 (Figs. 5 and 7) is provided so that the intensity condition can be accurately selected and in order to facilitate rotating the primer button 81 a knurled top cap 108 is located at the top of the button. For normal operation of the machine the primer button 81 should be disposed at its medium position illustrated in Figs. 7 and 8 where the bead 106 engages the slot 103 on the button. The guide strip 104 is springlike so as to hold the bead 106 normally in the slot 103 but possesses sufficient resiliency to allow the primer button 81 to be selectively rotated to the other positions.

We claim:

1. For use in a duplicating machine that comprises a drum, a cam on the drum adapted to rotate therewith, a moistening roller, a fountain disposed above the roller, and a wick mounted below the fountain and engaging the roller, the

combination of a reservoir for retaining a supply of fluid, a horizontally disposed cylinder, a piston in the cylinder, means providing a suction passage leading from the cylinder into the reservoir, a horizontally disposed shaft secured to the piston and mounted for reciprocating movement, spring means holding the piston at one end of the cylinder, intake valve means in the passage, means providing a discharge passage extending from the cylinder to the fountain, valve means in the discharge passage, and a pair of arm means each being pivoted adjacent one end and adjacent the other end engaging the shaft, one of the arm means being operatively connected to the cam to be pivotally rocked thereby so as to move the shaft against the force of the spring means, and a manual actuator connected to the other arm means to be pivotally rocked thereby so as to move the shaft against the force of the spring means, each of the arms being adapted to rock independently of the other arm.

2. For use in a duplicating machine that comprises a drum, a cam on the drum adapted to rotate therewith, a moistening roller, a fountain disposed above the roller, and a wick mounted below the fountain and engaging the roller, the combination of a reservoir for retaining a supply of fluid, a horizontally disposed cylinder above the reservoir and disposed closely adjacent to the top of the reservoir, a piston in the cylinder, means providing a suction passage leading from the cylinder downwardly into the reservoir and terminating adjacent to the bottom of the reservoir, a horizontally disposed shaft secured to the piston and mounted for reciprocating movement, spring means holding the piston at one end of the cylinder, intake valve means in the passage, means providing a discharge passage extending from the cylinder to the fountain, valve means in the discharge passage, and a pair of arm means each being pivoted adjacent one end and adjacent the other end engaging the shaft, one of the arm means being operatively connected to the cam to be pivotally rocked thereby so as to move the shaft against the force of the spring means, and a manual actuator connected to the other arm means to be pivotally rocked thereby so as to move the shaft against the force of the spring means,

each of the arms being adapted to rock independently of the other arm.

3. For use in a duplicating machine that comprises a drum, a cam on the drum adapted to rotate therewith, a moistening roller, a fountain disposed above the roller, and a wick mounted below the fountain and engaging the roller, the combination of a reservoir for retaining a supply of fluid, a horizontally disposed cylinder, a piston in the cylinder, means providing a suction passage leading from the cylinder into the reservoir, a horizontally disposed shaft secured to the piston and mounted for reciprocating movement, spring means holding the piston at one end of the cylinder, intake valve means in the passage, means providing a discharge passage extending from the cylinder to the fountain, valve means in the discharge passage, and a pair of arm means each being pivoted adjacent one end and adjacent the other end engaging the shaft, one of the arm means being operatively connected to the cam to be pivotally rocked thereby so as to move the shaft against the force of the spring means, and a manual actuator connected to the other arm means to be pivotally rocked thereby so as to move the shaft against the force of the spring means, each of the arms being adapted to rock independently of the other arm.
